CONTROL SWITCH FOR ELECTRIC
DISCHARGE LAMPS

Theodorus Hennenkamp and Klaas de Jong, Eindhoven, Netherlands, assignors to General Electric Company, a corporation of New York

Application April 26, 1947, Serial No. 744,064
In the Netherlands June 27, 1946

8 Claims. (Cl. 315—100)

1

This invention relates to an electric discharge device of the type employing ionizable mediums, such as gases or vapors, and more particularly to control switches for starting and operating electric discharge lamps.

Switches now in wide use with filament lamps are provided with means for heating the filamentary electrodes and for impressing a high voltage for a short duration upon the electrodes for starting an electric discharge therebetween. Means are provided in such switches to delay the application of the high voltage until the electrodes have reached the desired electron emitting temperature. When the discharge lamp does not ignite for some reason or other, the ignition arrangement continues its attempts to start the device. Usually the incapacity for starting is due to the loss of electron emission from one or both of the electrodes which may result from dissipation or other loss of activating material on which the emission depends. The large current, which then occurs on repeated starting attempts, is detrimental to the parts of the ignition arrangement and of the lamp installation. The continued flickering of the lamp due to the unsuccessful attempts of the starter to start the lamp produces light flashes undesirable for lighting purposes.

An object of our invention is to provide a new and improved time-delay lock-out switch.

Another object of our invention is to provide a new and improved starting and operating switch and circuit embodying means whereby after a limited number of unsuccessful attempts to start a lamp the starting operation is discontinued automatically.

A further object of our invention is to provide a starting and operating circuit comprising a switch embodying means for discontinuing the starting operation of the switch under abnormal conditions and which, upon deenergization is automatically restored to a condition for normal operation.

A still further object of our invention is to provide a new and improved time-delay lock-out switch which will operate as effectively on direct current as on alternating current installations.

Further features and advantages of our invention will appear from the following description and species thereof.

For a better understanding of our invention reference may be had to the following description taken in connection with the accompanying drawing and its scope will be pointed out in the appended claims. Fig. 1 is a diagrammatic view

2 showing the control switch connected together with a discharge lamp in an operating circuit. Fig. 2 illustrates diagrammatically a modification of the control switch shown in Fig. 1. Fig. 3 illustrates diagrammatically another modification of the control switch shown in Fig. 1. Fig. 4 illustrates diagrammatically a modification of the control switch shown in Fig. 3.

Referring to Fig. 1, the discharge device 1 therein comprises an elongated tubular or cylindrical envelope 2 having sealed into the ends thereof thermionic electrodes 3 and 4 which may be of the filamentary type each herein illustrated as comprising a coil, preferably in the form of a coiled coil of tungsten wire activated with the usual mixture of barium and strontium oxides. The envelope 2 contains an ionizable medium. This ionizable medium may comprise a rare gas like krypton, neon, argon or mixtures thereof at a pressure of a few millimeters and a small quantity of mercury which, during operation of the lamp, has a low pressure of the order of ten microns. The device 1 may be a low pressure positive column lamp of the fluorescent type with a suitable phosphor which under the influence of radiation from an electric discharge through the ionizable medium produces fluorescence.

In accordance with our invention the device 1 is connected across a suitable power supply circuit 5, 5', which for example may be a 118 volt, 60 cycle source, for supplying current to device 1 through the usual ballast 6 which serves as a starting inductance. A manual make-and-break control switch 7 may be used to connect device 1 to the power supply. We provide in series relation with the electrodes of device 1 or connected in parallel with the discharge path between electrodes 3 and 4, means comprising a parallel circuit, one branch of which includes in series relation a substantially instantaneously operating starting switch element and a time-delay or lock-out thermal switch element, and the other branch of which comprises actuating means for these elements, which actuating means may be constituted by separate means or a single unitary means. A starting and operating circuit 8, 8' comprising a parallel circuit, including two branches in series with the thermionic electrodes 3 and 4 of device 1, may include a starting switch 9 and a time-delay lock-out switch 10. The starting switch 9, for example, may be an electromagnet ignition arrangement provided with a magnetic actuating coil or winding 11 and a starting element such as an armature 12 provided with a contact member 13 for engagement with

a counter contact member 14. When the armature is not energized contact members 13 and 14 are held apart by means of a spring 15 tending to rotate the armature around the pivot point 16. The delay lock-out switch 10 comprises a time-delay element such as a bi-metal strip 17, provided with a contact member 18 which normally is in engagement with a counter contact member 19 while in the inactive or cold condition. A heating element 20, positioned in heat transfer relation with the bi-metal strip 17, serves as an actuating means for the delay lock-out switch 10.

One branch of the parallel circuit forming part of the starting and operating circuit 8, 8' contains the winding 11 in series with the heating element 20. The other parallel branch of circuit 8, 8' contains the armature 12 in series with the bi-metal strip 17.

When the entire installation is energized by closing switch 7, current flows through the ballast 6, thermionic electrode 4, winding 11, heating element 20, and thermionic electrode 3. The winding 11 actuates the armature 12 substantially instantaneously so that the contact members 13 and 14 engage each other and thus short circuit the parallel branch embodying the winding 11. The branch of the winding 11 is de-energized and the current limited by the inductance 6 flows through the thermionic electrodes 3 and 4. The de-energized winding 11 now releases the armature 12 and reduces the current flowing through the thermionic electrodes 3 and 4, and also rapidly reduces the current through the inductance 6. At this point the thermionic electrodes 3 and 4 are sufficiently heated to support an electrical discharge therebetween, and the induced voltage supplied by the inductance 6 initiates an arc discharge between the electrodes. When the discharge has taken place, the voltage between the electrodes 3 and 4 drops to an operating voltage, as for example 60 volts. The winding 11 is so designed that the current which passes at this reduced voltage, through the winding does not attract the armature 12 to the degree necessary to close contacts 13 and 14.

When the device 1 does not ignite at the first opening of the contacts 13 and 14, the armature 12 is attracted anew, the contact elements 13 and 14 close again, and allow a suitable current to flow through the electrodes 3 and 4 and open again upon de-energization of winding 11. This action is repeated so long as the discharge device 1 does not ignite.

If the device 1 refuses to ignite after repeated ignition attempts, the bi-metallic strip 17 becomes heated by means of the starting current flowing through element 20 and bends in an upward direction so that the contact members 18 and 19 of the delay lock-out switch 10 separate. Element 20 keeps these contacts in open position until the device is disconnected from the power supply 5, 5'. After interruption of the power supply heating element 20 cools and allows contact members 18 and 19 to re-engage each other.

The heating element 20 and the bi-metallic strip 17 are so matched with each other that the actuating effect of the heating element 20 upon the bi-metallic strip 17 takes effect only after repeated attempts by the discharge device 1 to ignite. Adjustments of this type may be obtained by varying the distance between element 20 and member 17, varying the medium between them, or by varying the contact pressure between contact members 18 and 19. Heating element 20 may be of any suitable type, for example, a

resistor or as illustrated in Fig. 2 a small glow-discharge tube 21. In either case the heating element 20 may be designed to act as a source of light as well as heat, and thereby act as a signal to warn that the installation is energized and that the delay lock-out switch is in operation.

As has already been indicated, the ignition arrangement may be adjusted to the discharge device 1 in such a manner that the winding 11 does not attract the armature 12 after the discharge device 1 has ignited the current through the branch including the magnetic winding 11 is lower than when the tube has not ignited. Arrangements can be made to reduce the current through the branch of the magnetic winding 11 to zero while device 1 is operating. If the current flowing through the branch including the winding 11, when the discharge device 1 is operating, is large enough it may cause the delay lock-out switch to operate. This will have the result that, when device 1 is operating, contact members 18 and 19 will be separated by heating element 20. This is permissible; however, in some cases it is desirable to replace a disconnected device or lamp immediately. In which case the lock-out switch 10 will cause a delay until bi-metallic strip 17 cools. It is therefore advantageous to match the heating element 20 and the bi-metallic strip 17 so that strip 17 will be actuated by means of heating element 20 only by a current larger in value than that passing through the branch including the winding 11 while device 11 is operating.

It is particularly advantageous to use the winding 11 as the heating element 20. Thus the winding 11 may serve a dual function. According we provide, as illustrated in Fig. 3, a modification of the control switch shown in Fig. 1 wherein the winding 11 serves also as the heating element. The bi-metallic strip 17 is mounted along side the cylindrical spool of the magnetic winding 11. As soon as the spool reaches the required temperature the bi-metallic strip 17 bends to the left in the direction of the arrow so that the lock-out switch contacts 18 and 19 separate from each other, and thus open the branch circuit embodying contact elements 13 and 14 of the starter switch 9. The iron circuit of the magnet is represented by the core 22 of winding 11 and the armature 12.

Fig. 4, illustrating a modification of Fig. 3, provides a unitary starting and time-delay lock-out switch wherein winding 11 serves as a common actuating means for the starting element and the time-delay element. Winding 11 is connected in shunt across the starting element and the time delay element. Bi-metallic strip 17 of the thermal time-delay switch 10 is replaced by a bi-metallic strip 23 which is mounted adjacent to and in heat transfer relationship to winding 11. Counter-contact member 14 of the starter switch 9 and counter-contact member 19 of the time delay lock-out switch 10 are omitted. The armature 12 and the bi-metallic strip 23 are positioned substantially perpendicular to each other. Contact member 18 works with the bi-metallic strip 23 as the counter-contact member of the contact member 13. Contact member 13 is supported by armature 12 and moves therewith upon actuation of the armature. As soon as the spool of the winding 11 reaches the required temperature, the bi-metallic strip 23 bends to the left in the direction of the arrow, breaking engagement with contact member 13, moving out of reach of ar-

mature 12 and thus opens the circuit of the starting and operating switch assembly.

In accordance with our invention, we provide a starting and operating switch which, after a limited number of unsuccessful attempts to start a lamp, discontinues the starting operation automatically. Accordingly we provide a starting and operating switch embodying means for discontinuing the starting operation of the switch under abnormal conditions and which upon de-energization is automatically restored to an initial condition for normal operation.

Generally speaking we provide a time-delay lock-out switch and circuit therefor which will eliminate flickering, reduce voltage and current supplied to a defective lamp, and protect the lighting installation from excessive currents. In addition this improved time-delay lock-out switch will operate as effectively on direct current as on alternating current installations. The above described circuits and devices may be applied with equal facility to instant start electric discharge devices and lamps as well as pre-heat devices and lamps. The devices above described are not limited to the circuits therewith described.

What we claim as new and desire to secure by Letters Patent of the United States is:

1. In combination, a supply circuit, an electric discharge device having at least one filamentary electrode, and means connected in series with said electrode for controlling and starting said device comprising means including a magnetically actuated starting element, a time-delay lock-out means and an actuating means, said time-delay lock-out means including a thermal element and said actuating means being connected across said starting element and said thermal element.

2. In combination, a supply circuit, an electric discharge device having at least one filamentary electrode, and means for controlling and starting said device connected in series with said electrode and comprising a parallel circuit including a magnetic switch provided with contacts and an actuating coil therefor and a time-delay switch provided with an actuating means therefor, said actuating coil for said magnetic switch and actuating means for said time-delay switch being connected in series relation and constituting one branch of said parallel circuit, the contacts of the switches being connected in series relation across the actuating means.

3. In combination, a supply circuit, an electric discharge device having at least one filamentary electrode, and means for controlling and starting said device connected in series with said electrode and comprising a parallel circuit including a magnetic starting switch with contacts and an actuating coil therefor and a thermal time-delay switch having thermally actuated contacts and a heating element therefor, said actuating coil for said starting switch and said heating element for said time-delay switch being connected in series relation and constituting one branch of said parallel circuit, the contacts of the switches being connected in series relation across the actuating coil and heating element.

4. In combination, a supply circuit, an electric discharge device having at least one filamentary electrode, and means for controlling and starting said device connected in series with said electrode

and comprising a parallel circuit including a magnetic starting switch with contacts and an actuating coil and a thermal time-delay switch having bi-metallic contacts and a heating element comprising a glow discharge tube in close proximity thereto, said actuating coil for said starting switch and said glow discharge tube for starting said time-delay switch being connected in series relation and constituting one branch of said parallel circuit, the contacts of the switches being connected in series relation across the actuating coil and glow discharge tube.

5. In combination, a supply circuit, an electric discharge device having at least one filamentary electrode, and means for controlling and starting said device connected across said device and comprising a parallel circuit including magnetically responsive contact means and thermally responsive time-delay contact means connected in series relation and constituting one branch of said parallel circuit, and actuating means for supplying magnetic energy to said magnetically responsive contact means and thermal energy to said thermally responsive contact means, said actuating means being connected across said magnetically responsive contact means and said thermally responsive contact means.

6. In combination, a supply circuit, an electric discharge device having at least one filamentary electrode, and means for controlling and starting said device connected across said device and comprising a parallel circuit including a magnetic switch provided with contacts and an actuating coil therefor and a thermal time-delay switch mounted in heat-transfer relationship to said coil, said coil comprising one branch of said parallel circuit, the contacts of the switches being connected in series relation across the said coil.

7. In combination, a supply circuit, an electric discharge device having at least one filamentary electrode, and means for controlling and starting said device connected across said device and comprising a parallel circuit including a magnetic switch provided with a movable contact member and an actuating coil therefor and a thermal time-delay switch comprising a bimetallic member mounted in heat-transfer relationship to said coil and carrying a contact normally in position to be engaged by the said movable contact member of the magnetic switch, said bimetallic member being arranged to carry, when heated, its said contact out of the path of movement of the said movable contact member of the magnetic switch, said actuating coil comprising one branch of said parallel circuit, the said contacts of the switches being connected in series relation across the said coil.

8. The combination set forth in claim 3 wherein the said heating element is designed to emit light when the contacts of the time-delay switch are open.
